UNITED STATES PATENT OFFICE.

GEORGE R. AINSWORTH, OF GREAT NECK, NEW YORK.

DESIGN FOR AN ELECTRIC-LIGHT FIXTURE.

50,333.

Specification for Design.

Patented Feb. 20, 1917.

Application filed October 6, 1916. Serial No. 124,201. Term of patent $3\frac{1}{2}$ years.

To all whom it may concern:

Be it known that I, GEORGE R. AINSWORTH, a citizen of the United States, and a resident of Great Neck, Nassau county, New York, have invented a new, original, and ornamental Design for Electric-Light Fixtures, of which the following is a specification, reference being had to the accompanying drawing, in which the figure shows a front elevation of a fixture embodying my invention.

The design comprised in this invention

consists of a flattened disk carrying on its face an ornamental medallion. From the top and bottom of the disk extend ornaments in the form of flattened conventional flower buds, from the top bud extend a plurality of arms for carrying lights, and ornaments such as shown hang from beneath the light-holding portions of the arms.

What I claim is:

The ornamental design for an electric light fixture as shown and described.

GEORGE R. AINSWORTH.
